UNITED STATES PATENT OFFICE.

HAROLD MESTRE, OF SAN FRANCISCO, CALIFORNIA.

TABLE-SEAT.

1,375,166.

Specification of Letters Patent. Patented Apr. 19, 1921.

Application filed August 7, 1919. Serial No. 315,851.

To all whom it may concern:

Be it known that I, HAROLD MESTRE, a citizen of the United States, and a resident of the city and county of San Francisco and State of California, have invented a certain new and useful Table-Seat, of which the following is a specification.

My invention relates to improvements in table seats and has for its primary object the provision of a cheap, strong, durable and simply constructed seat for packing-tables in canneries and the like where a great many operators or workers take positions for work along the tables.

Another object of the invention is to provide a table seat of the character described which when not in use may be swung or moved into an out-of-the-way position.

A further object of the invention is to provide a table seat which when occupied is held in position so that it cannot easily swing or move as the occupant moves while working and which while readily movable when unoccupied, tends to remain in the position in which it is placed.

The invention possesses other advantageous features, some of which, with the foregoing, will be set forth at length in the following description where I shall outline in full, that form of the invention which I have selected for illustration in the drawings accompanying and forming part of the present specification. In said drawings I have shown one form of the device of my invention, but it is to be understood that I do not limit myself to such form, since the invention, as expressed in the claims, may be embodied in a plurality of forms.

Referring to said drawings:

Figure 1 is a fragmentary side elevation of a packing-table showing the seats of my invention attached thereto.

Fig. 2 is a perspective view of the seat support showing it attached to the leg of the table.

Fig. 3 is a perspective view of the seat proper.

Fig. 4 is a top plan view of one of the two locking plates.

Fig. 5 is a fragmentary side elevation of a part of the supporting means for the seat showing the spring means employed.

In accordance with my invention there is provided a seat member which is supported by a horizontal supporting bar which bar is preferably formed of a straight piece of

rolled channel iron. The seat member has a standard which is vertically adjustably mounted in one end of the supporting bar. The supporting bar is pivotally secured by a bracket to the standard or leg of the packing-table, or to any other suitable support, and the bracket is preferably constructed to support two supporting arms so that two seats may be attached to each table leg.

Serrated plates are mounted on the bar and bracket respectively to frictionally engage one another so that when the seat is occupied the weight of the occupant will force the plates into close frictional engagement and thus restrain the bar and seat against free movement. The plates, when the seat is unoccupied, frictionally engage sufficiently to prevent unintentional movement of the bar so that the seat tends to remain in the position in which it is placed whether occupied or unoccupied but when unoccupied may be readily moved as desired. I may employ spring means to force the plates together so as to insure sufficient restraining action to cause the seat to remain in the position in which it is placed when not occupied.

As shown in Fig. 1 of the drawings, several seats, constructed in accordance with my invention, are attached to the packing-table 1, that is, to the legs 2 of said table.

The seat of my invention comprises a seat member 5, depending from the center of which is a standard 6. The standard 6 is provided with a series of transverse openings 7 arranged one above the other therein.

Secured to the table leg 2 by a bracket 8, formed of the two angles 21 and 22, is a horizontal channel iron supporting bar 9. A pivot pin 10 is inserted through the bracket and bar to pivotally secure the bar to the bracket. The bracket is large enough to support another bar for an additional seat so that two seats may be connected with each table leg. The bar 9 is provided in its outer end with aligned openings 11 through which the standard 6 of the seat 5 extends. A pin 12, which is secured to the seat by a chain 13, is inserted through one of the openings 7 in the standard and rests upon the bar 9 to hold the seat in adjusted position. Secured to the upper end of the standard 6 is a cast spider 23 which is cast about the end of the spindle in a chill and the seat 5 is suitably secured to the spider.

There is provided means to restrain the

seat against swinging out of position when occupied and for preventing unintentional movement of the seat when unoccupied. This means comprises a sheet metal plate 14, 5 mounted on the bar 9 and resting upon a similar plate 15 mounted on the bracket 8. Each plate is provided on one edge with a right angularly disposed flange 16 which engages the respective edge or side face of the bar and bracket to prevent the plates from slipping relative to the bar and bracket. Openings 17 are formed in the plates and the pin 10 passes through said openings to hold the plates in place. I may use a spring 15 24 mounted on the pin 10 between the angle 21 and bar 9 so as to force the bar downwardly and cause the plates 14 and 15 to frictionally engage and check the bar against unintentional movement. The opposed faces of these plates are serrated, that is, are provided with ridges or protuberances 18 arcuately arranged and adapted to engage one another and hold the seat in position when the plates are forced together by 20 the weight of the occupant on the seat or by the spring 24.

In moving the seat and bar when the seat is unoccupied the ridges 18 on the plates 14 and 15 will ride over one another freely 30 and not interfere with the desired movement of the seat. The bar has sufficient vertical play on its pivot pin 10 to permit the spring 24 to yield and allow the bar to be freely moved. The weight of the bar and 35 seat is ordinarily sufficient to cause the plates 14 and 15 to so frictionally engage that unintentional movement of the seat when unoccupied is prevented, but to insure the prevention of this unintentional movement I may use the spring 24 hereinbefore described.

The seat member 5 may be vertically adjusted to the height to suit the particular occupant by raising or lowering the standard 45 6 in the openings 11. After the seat is adjusted as desired it may be held in such position by inserting the pin 12 through the proper opening 7 so that the pin will rest on the bar 9.

With the construction hereinbefore described I provide a cheap, strong table seat which will take up little or no room, and will provide maximum comfort commensurate with efficiency and convenience of use. 50

I claim:

1. A table seat structure comprising a pair of bracket members with flanges adapted to be attached in spaced and horizontal position on a fixed supporting part, a carrying 55 bar formed of channel iron having alined holes through its flanges at one end to receive a pin mounted in the said bracket flanges, and a standard passed through apertures in the flanges of the opposite end of

the bar, said standard having a seat on its 65 upper end.

2. A table seat comprising a horizontal channel iron bar disposed with its web upright, a bracket adapted to be secured to a support, a pivot pin extending vertically 70 through the bracket and the flanges of the bar, a seat standard vertically adjustable on the bar, and a seat secured to the standard.

3. A table seat comprising a bracket 75 adapted to be secured to a support, a horizontal bar pivoted to the bracket and having a flange overlapping the bracket, a seat mounted on the bar, and means to restrain the swinging of the bar against movement 80 on its pivot when the seat is occupied, comprising serrated plates mounted on the bar and bracket respectively and disposed between the overlapping flange of said bar and the bracket.

4. A table seat comprising a bracket adapted to be secured to the table, a seat supporting bar, a pivot pin extending through the bar and bracket, serrated plates disposed in engagement with one another 90 between the bar and bracket, said plates having openings therein through which the pin extends, a seat mounted on said bar, and flanges on the plates engaging the side faces of the bar and bracket.

5. A table seat comprising a pair of angle irons adapted to be secured to a table leg in spaced relation vertically, a pivot pin extending vertically through said angles, a rolled channel iron bar engaging said pin 100 and having its end disposed between said angles, said bar being provided at its other end with vertically alined openings, a seat spindle mounted in said openings, a spider chilled to the end of said spindle and a seat 105 secured to said spider.

6. A table seat structure comprising a pair of angle irons forming a bracket, a channel iron bar disposed with its web perpendicularly to parallel flanges of the angle iron, a pivot pin passing through said flanges and the flanges of the said bar, a seat having a standard mounted rotatively in the swinging end of the bar and passing through the flanges thereof.

7. A table seat comprising a bracket adapted to be secured to a support, a bar pivoted to the bracket, a seat mounted on the bar, a serrated plate on the bar, a serrated plate on the bracket and engaging the 110 first named plate, and a spring tending to force the plates together.

In testimony whereof, I have hereunto set my hand at San Francisco, California, this 26th day of July, 1919.

HAROLD MESTRE.

In presence of—
C. S. EVANS.
